UNITED STATES PATENT OFFICE.

JAMES G. PENNYCUICK, OF TORONTO, CANADA, ASSIGNOR TO THE LUXFER PRISM PATENTS COMPANY, OF CHICAGO, ILLINOIS.

DESIGN FOR A VAULT-LIGHT.

SPECIFICATION forming part of Design No. 26,989, dated April 27, 1897.

Application filed March 18, 1897. Serial No. 628,222. Term of patent 14 years.

To all whom it may concern:

Be it known that I, JAMES G. PENNYCUICK, a subject of the Queen of England, residing at Toronto, in the county of York, Province of Ontario, Dominion of Canada, have invented a certain new and useful Design for Vault-Lights, of which the following is a description.

My invention relates to a new and improved design for vault-lights and is illustrated in the accompanying drawings, wherein—

Figure 1 is a side view of the vault-light embodying my invention. Fig. 2 is a front view of the same. Fig. 3 is a plan view of the same.

The vault-light consists of a body portion

provided with the projecting prism A', having the surface B, substantially perpendicular to the body portion A, and the oblique surface C. Connected with the body portion A is an ²⁰ upwardly-projecting circular piece D.

The essential feature of my design is a vault-light having a body portion provided with the projecting prism A' on one side and on the other side with the circular projection D. ²⁵

I claim—

The design for vault-lights as herein shown and described.

JAMES G. PENNYCUICK.
